UNITED STATES PATENT OFFICE.

HAROLD B. ROSE, OF HORNELLSVILLE, NEW YORK.

DESIGN FOR A PHOTOGRAPHIC MOUNT.

SPECIFICATION forming part of Design No. 34,465, dated April 30, 1901.

Application filed April 4, 1901. Serial No. 54,402. Term of patent 7 years.

To all whom it may concern:

Be it known that I, HAROLD B. ROSE, a citizen of the United States, residing at Hornellsville, in the county of Steuben and State of New York, have invented a new and original Design for a Photograph-Mount, of which the following is a specification.

My invention relates to a new and original design for photograph-mounts and is illustrated in the accompanying drawing, in which the figure is an elevation.

My design resides in a photograph-mount, the leading or material feature of which consists in an ornamentation in the shape of a foot-ball having a series of openings in its side.

In the said drawing the reference-numeral 1 indicates the base or ground of the photo-

graph-mount, and 2 indicates the ornamentation in the shape of a foot-ball having a series of openings 3 in its side.

My design presents a photograph-mount of novel, pleasing, and distinguished appearance.

Having thus described my invention, what I claim is—

The design for a photograph-mount, substantially as herein shown and described.

In testimony whereof I have hereunto set my hand in presence of two subscribing witnesses.

HAROLD B. ROSE.

Witnesses:
